UNITED STATES PATENT OFFICE.

SAMUEL M. CAWKER, OF DENVER, COLORADO.

NON-REFILLABLE BOTTLE.

SPECIFICATION forming part of Letters Patent No. 727,534, dated May 5, 1903.

Application filed December 9, 1902. Serial No. 134,580. (No model.)

To all whom it may concern:

Be it known that I, SAMUEL M. CAWKER, a citizen of the United States of America, residing in the city of Denver and State of Colorado, have invented certain new and useful Improvements in Non-Refillable Bottles; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in non-refillable bottles; and it consists in locating in the neck of the bottle an air-storage chamber into which sufficient air or gas may be compressed to fill the bottle, the said chamber having a valve controlled from the outside, whereby air or gas may be admitted to the bottle to force the liquid out. The air in the said chamber is compressed to a number of atmospheres, so that when released it 25 will expand to fill the bottle at normal atmospheric pressure, but no more. Hence after the bottle is once emptied it cannot be refilled, or, if refilled, it cannot be emptied, as there is no opportunity for air or gas to 30 get into the bottle to take the place of the liquid, the receptacle or chamber in the neck of the bottle having no communication with the external atmosphere. Provision is also made for locking the valve in the closed position as soon as the bottle is empty, so that if the receptacle was bored to let in air it 35 could not escape into the bottle by the manipulation of the valve or otherwise.

Having briefly outlined my improved construction, as well as the functions it is intended to perform, I will proceed to describe the same in detail, reference being made to the accompanying drawings, in which is illustrated an embodiment thereof.

45 In the drawings, Figure 1 is a section taken through a bottle equipped with my improvements. Fig. 2 is a sectional view of the air-chamber shown in detail and on a larger scale. Fig. 3 is a section taken on the line 50 3 3, Fig. 1. Fig. 4 is a fragmentary section of the air-chamber, showing the valve-stem-

locking device held open to allow the stem to move freely. Fig. 5 is a similar view showing the locking device released. These views are taken on the line 4 5, Fig. 2, viewed in the 55 direction of the arrow.

The same reference characters indicate the same parts in all the views.

Let the numeral 5 designate the neck of the bottle, in which is located a cylindrical air-chamber 6, the latter being provided with exterior ribs 6^a and held in place by cement 7. Formed in the neck of the bottle adjacent the chamber 6 is a recess in which is located a tube or conduit 8, preferably composed of 65 glass and extending into the lower part of the bottle, preferably terminating as close to the bottom as practicable without closing the open end of the tube. This is preferably provided exteriorly with a bent portion 8^a, 70 whose free end is directed downwardly for convenience in drawing the liquid from the bottle. Passing through the chamber 6 is a tube 9, which is secured in the heads 6^a and 6^c of the chamber, the latter being prefer- 75 ably composed of steel or other suitable material adapted to give the required strength with a minimum weight and thickness. This tube passes through the lower head or bottom 6^c of the chamber and protrudes suffi- 80 ciently to form a nipple for the attachment of an air-pump, which may be employed in compressing the air within or charging the chamber 6. For this purpose the protruding end of the tube is threaded, as shown at 9^a. 85 Within the tube 9 is located a stem 10, whose lower extremity is tapering and forms a valve, which fits closely in a counterpart seat formed in the lower portion of the tube. The lower extremity of this stem is outwardly flared to 90 engage a shoulder formed on the tube to prevent the withdrawal of the stem from the tube. This tapered portion of the stem is hollow, as shown at 10^a, and this hollow portion communicates with a transverse opening 95 10^b, formed in the stem and adapted when the latter is properly adjusted to register with an opening 9^c, formed in the tube and communicating with the air-space within the chamber. Above the orifice 10^b a recess 10^d is formed in 100 the tube to receive a stud 12, mounted on a leaf-spring 13, attached to the tube 9 and lo-

cated in the chamber. This tube is provided with an opening 9^g to receive the stud, and when the stem 10 is properly adjusted the spring throws the stud into the recess 10^d and locks the stem from turning. The relative arrangement of the orifices 9^e and 10^e is such that when the stud 12 engages the recess 10^d the said orifices do not register, and consequently there is no communication between the chamber 6 and the interior of the bottle when the stem is locked. The lower extremity of the spring 13 is bent to occupy a horizontal position, as shown at 13^a, and this horizontal portion is provided with a notch 13^b. Mounted on the bottom or lower head of the cylindrical air-chamber is a flexible diaphragm 14, having a space beneath closed from the space within the chamber, but communicating with the bottle by an orifice 15. Normal atmospheric pressure keeps this diaphragm raised, and mounted upon it is a projection 16, adapted to engage the notch of the spring and hold the latter outwardly, whereby the stud is prevented from entering the recess of the stem 10. Before the chamber 6 is closed and sealed the spring 13 is drawn outwardly and the stem turned to prevent the stud 12 from entering the recess 10^d, and so that the orifices 9^e and 10^e shall register. The chamber 6 is then sealed and air introduced by connecting an air-pump (not shown) with the threaded protruding part 9^a of the tube 9. The air is compressed in this chamber until the pressure-gage (not shown) indicates a pressure of a number of atmospheres equal to the number of times the volume of the air-chamber is contained in the volume of the bottle. If the contents of the bottle equal twenty times the contents of the air-chamber, the pressure-gage must indicate twenty atmospheres, which at the sea-level would be three hundred pounds. Of course the pressure in pounds required in any given case will vary with the elevation, but the relative number of atmospheres of course never varies. The required pressure in the chamber 6 will depress the diaphragm 14 and bring the projection 16 into the notch 13^b of the spring, thus preventing the stud 12 from entering the recess 10^d of the device and permitting the stem to be turned freely without danger of locking by engagement with the stud. As soon as the air-chamber is prepared—that is to say, as soon as the pressure therein reaches the proper number of atmospheres, as indicated by the pressure-gage—the stem is turned to cut off communication between the orifices 9^e and 10^e, thus closing the chamber to prevent the escape of air. The air-chamber is then placed in the neck of the bottle, the latter being first filled with its liquid contents and securely sealed by the use of cement or in any other suitable manner. Then whenever it is desired to draw liquid from the bottle or other vessel containing my invention the stem 10 is turned to cause the orifices 9^e and 10^e to register, where-

by air from the chamber 6 escapes into the bottle and forces the liquid out through the tube 8 into a glass or other receptacle held beneath the nozzle of the part 8^a. After the liquid has all been drawn out of the bottle there will be normal atmospheric pressure in the air-chamber and bottle and the diaphragm 14 will rise and release the spring 13, and as soon as the stem 10 is turned sufficiently the stud 12 will enter the recess 10^d and lock the stem against turning. There is now no way to get more air into the chamber 6 without boring a hole in the upper head of the air-chamber, and if this was resorted to there would be no way of releasing the air to control the discharge of the liquid from the bottle even if the latter could be refilled. Hence the device may be properly called a "non-refillable bottle."

It must be understood that wherever the term "air" is used in the specification and claims air or gas must be understood, since it is evident that gas, wherever practicable, may be employed as well as air for filling the air or gas chamber without in any way departing from the spirit of the invention.

Having thus described my invention, what I claim is—

1. In a device of the class described, the combination with a bottle or other similar vessel adapted to contain liquid, of a chamber adapted to contain compressed air or gas, said chamber being located in the neck of the bottle or vessel, and means for releasing the air or gas to allow it to enter the bottle and force out the liquid.

2. The combination with a bottle, of an air or gas chamber located in the neck thereof and having the air therein sufficiently compressed to fill the bottle at normal atmospheric pressure, and a valve connected with the air-chamber to control the escape of air to the bottle.

3. The combination with a bottle or similar liquid-containing vessel, of an air or gas chamber located in the upper part thereof, the air being sufficiently compressed to exactly fill the bottle at normal atmospheric pressure, and means for controlling the release of the air into the bottle for the purpose of ejecting the liquid, and a conduit connected with the bottle for the escape of the liquid.

4. The combination with a bottle or other similar liquid-containing vessel, of an air or gas chamber located in the upper part thereof and containing air compressed to a predetermined degree, a conduit leading from the bottom of the bottle and communicating with the atmosphere, and a valve connected with the air-chamber for controlling the escape of air to the bottle.

5. The combination with a bottle, of an air or gas chamber securely sealed in the neck thereof and provided with air or gas compressed to a predetermined degree, a valve for controlling the escape of air from the cham-

ber to the bottle, and a conduit through which the air or gas entering the bottle forces the liquid, substantially as described.

6. The combination with a bottle, of an air-chamber inserted in the neck thereof and securely fastened, a tube passing through the air-chamber and made fast in the ends of the latter, its lower extremity protruding and being threaded to form a nipple for the attachment of an air-pump, a stem located in said tube and having its lower part outwardly flared to fit a seat in the tube and arranged to prevent withdrawal, the valve-stem having an opening communicating with the interior of the bottle and arranged to register with an orifice formed in the tube whereby communication is established between the interior of the bottle and the interior of the chamber, the upper extremity of the stem protruding from the air-chamber to permit the manipulation of the valve outside.

7. The combination with a bottle, of an air-chamber inserted in the neck of the bottle and securely fastened, a tube passing through the air-chamber and made fast therein, a stem located in said tube and having its lower extremity outwardly flared to fit a seat in the tube, the valve-stem having an opening communicating with the interior of the bottle, and arranged to register with an orifice formed in the tube, the upper extremity of the stem protruding from the air-chamber to permit manipulation from the outside, and suitable means connected with the air-chamber for locking the valve-stem against turning when the orifice of the valve and stem are out of register.

8. The combination with a bottle, of an air-chamber inserted in the neck thereof and fastened in any suitable manner to form a tight joint around the said chamber, a tube passing through the chamber and made fast in the ends thereof, a stem located in said tube and having an orifice arranged to register with an orifice formed in the tube to establish communication between the interior of the air-chamber and the interior of the bottle, the said communication being opened and closed at pleasure by the manipulation of the stem, a leaf-spring attached to the tube within the air-chamber and provided with a stud adapted to enter a recess formed in the valve-stem when the latter is properly adjusted.

9. The combination with a bottle, of an air-chamber secured in the neck thereof and provided with a passage leading from its interior to the interior of the bottle, a valve-stem located in the air-chamber and arranged to control said passage, a leaf-spring located within the chamber and provided with a stud

adapted to enter a recess formed in the valve-stem when the latter is properly adjusted, and means located within the air-chamber for automatically holding the spring in position 65 to prevent the stud from entering the recess of the stem, when the air within the chamber is compressed as described.

10. The combination of a chamber adapted to hold air compressed to a predetermined degree, a tube passing through said chamber and protruding to form a nipple for the attachment of an air-pump, a valve-stem located within the tube and having an orifice communicating with the nipple end of the 75 tube, the latter being also provided with an orifice arranged to register with the orifice of the stem when the latter is properly adjusted, a leaf-spring located in the air-chamber and provided with a stud normally adapted to enter a recess formed in the valve-stem when the latter is properly adjusted and when the orifices of the stem and tube are out of register, the said orifices being arranged with regard to this feature, a flexible diaphragm formed 85 in the bottom of the air-chamber and provided with a projection, the spring having a notch which is entered by the projection of the diaphragm when the latter is depressed by the air of the chamber, substantially as described. 90

11. The combination with a bottle, of an air-chamber located in the neck thereof and containing air compressed to a predetermined degree, the chamber having a valve-controlled passage leading from its interior to the interior 95 of the bottle.

12. The combination with a bottle, of an air-chamber located in the neck thereof and containing air compressed to a predetermined degree, the chamber having a passage leading from its interior to the interior of the bottle, and a valve for controlling said passage, the valve being arranged to be manipulated from the outside of the air-chamber. 100

13. The combination with a bottle, of an air-chamber secured within the neck thereof and adapted to hold air compressed to any desired degree, means for controlling the release of said air into the bottle to force out the liquid, and an open-ended tube leading from the bottom of the bottle and extending upwardly through the neck of the latter which is provided with a recess to receive the tube, the latter occupying a position adjacent the exterior wall of the air-chamber. 105 110 115

In testimony whereof I affix my signature in presence of two witnesses.

SAMUEL M. CAWKER.
